DESIGN FOR AN EDUCATIONAL TOY FOR CHILDREN

Henry Shrier, Forest Hills, N. Y.

Application June 29, 1945, Serial No. 120,408

Term of patent 3½ years

(Cl. D34—15)

To all whom it may concern:

Be it known that I, Henry Shrier, a citizen of Poland, residing in Forest Hills, county of Queens, and State of New York, have invented a new, original, and ornamental Design for Educational Toy for Children, of which the following is a specification, reference being had to the accompanying drawing, forming part thereof.

In the drawing:

Fig. 1 is a front elevational view of an educational toy for children showing my new design;
Fig. 2 is a top plan view thereof; and
Fig. 3 is a rear elevational view thereof.

I claim:

The ornamental design for an educational toy for children, substantially as shown.

HENRY SHRIER.
